FOREIGN PATENT DOCUMENTS

WO 99/22958 5/1999

Primary Examiner — Cynthia Underwood

(74) Attorney, Agent, or Firm — Dority & Manning, P.A.

(57) **CLAIM**

The ornamental design for a landing gear adapter for trailer chassis, as shown and described.

DESCRIPTION

FIG. 1. is a perspective view of a landing gear adapter for trailer chassis according to the present design;

FIG. 2 is a front side view of the adapter of FIG. 1;

FIG. 3 is a back side view of the adapter of FIG. 1;

FIG. 4 is a top side view of the adapter of FIG. 1;

FIG. 5 is a bottom side view of the adapter of FIG. 1;

FIG. 6 is a right side view of the adapter of FIG. 1;

FIG. 7 is a left side view of the adapter of FIG. 1; and,

FIG. 8 is an alternate perspective view of the adapter of FIG. 1.

The broken lines represent environment and form no part of the claim.
